BRACKET FOR ATTACHMENT TO PIT PROPS,
STANCHIONS, BEAMS, AND THE LIKE

Walter Sylvester, Tunstall, England

Application April 22, 1938, Serial No. 203,530
In Great Britain April 24, 1937

4 Claims. (Cl. 248—221)

This invention relates to brackets for attachment to pit props, stanchions, beams and the like, hereinafter generically termed "posts," and particularly to props and other supports used in mines for the purpose of carrying sprags or struts, cables and the like. For simplicity the invention will be described as applied to brackets for pit props.

It is frequently desirable in coal mines, especially where coal cutting machines are employed, to provide support for the coal face and/or roof immediately adjacent thereto so as to prevent premature falls as the machine undermines the coal, which falls are not only a danger to the miners but may damage the machine or at least cause expensive delay in its operation. Supports or sprags are often required for other purposes, for example, to carry beams, cables, etc. It is not practicable to fit such supports from the ground as they would be in the way of the machine as it travels along the coal face and the only practicable method is to attach additional and inclined supports to the first line of props so as to spring from a point well above the floor level.

Where metal pit props are used this calls for some form of clamp or bracket but the practical conditions have to be considered. Firstly, a miner does not normally carry a spanner or wrench and naturally objects to such addition to his equipment. Secondly, it is an accepted fact that bolts and nuts are impracticable in a mine, because of their short life as they soon become bent or their threads damaged quite apart from the percentage of loss under the conditions of use. Fittings secured by bolts take time to fit and moreover, depend for their safety upon proper tightening of the bolts which if too slack or too tight are a source of danger which cannot be ignored where speed is required and labour unskilled in their use.

The object of the invention is a bracket or clamp which can be quickly and easily fitted, adjusted and securely fixed in position on a pit prop without a spanner or other special tool.

According to the invention a bracket for a post comprises a body part, a cam formed on the body part adapted to engage the side of the post and complementary means co-acting with the cam to form clamping means for fixing the bracket to the post, the body part being formed to support the end of a strut so that the thrust therefrom operates to tighten the clamp.

In the accompanying drawing:

55 Fig. 1 is a side elevation of one example of bracket made in accordance with the invention.

Fig. 2 is a plan of Fig. 1.

Fig. 3 is a plan showing a modification of Fig. 1.

60 Fig. 4 is a side elevation of a modified form

of bracket made in accordance with the invention.

Fig. 5 is a plan of Fig. 3.

Fig. 6 shows an alternative construction of the example shown in Fig. 1.

Fig. 7 shows a further modification of bracket.

As illustrated in Figs. 1 and 2, the improved bracket is of welded steel construction and comprises a rest or socket *a* adapted to receive the end of a strut *b*, which rest or socket is attached to triangular extensions of three cams *c*, *c*¹ and *c*² made from quarter inch steel plate. A curved plate *d* is welded to the ends of the cams to unite them into a body and form a single cam of the full width of the standard girder prop *e* to which it is shown attached. Through the axis of the cams is a stout spindle, about 1 inch diameter, formed in two parts *f* and *f*¹ which are halved at their inner ends and overlap, and to the outer end of each part is secured an arm *g* having an inwardly projecting claw *g*¹. Both parts of the spindle are rotatable in the cams, but one of them *f*¹ is also slidable to allow the arm to open wide enough to pass the claws over the flange of the girder prop. A stop *h* is provided in the part *f* of the spindle to prevent any sliding movement, while a stop *h*¹ is provided in the part *f*¹ to limit the sliding movement. In all positions, however, the centre cam *c*¹ supports the divided ends of the parts *f* and *f*¹ of the spindle so that they are also constrained to rotate together. The stop *h*¹ on the sliding part *f*¹ of the spindle is also adapted to engage a lug *i* secured to the inside of the adjacent cam *c* and shaped so that the arm secured thereto can only be moved to the open position while the jaws are opposite the small part of the cam and both arms and parts of the spindle are locked from rotation when in such open position.

As will be seen, the bracket has no detachable parts or nuts or bolts to be tightened. In use, the arms or body are easily rotated to the position shown in broken line in Fig. 1 when the sliding arm can be moved outwards to the open position shown in broken line in Fig. 2. The bracket is then easily fitted laterally to the flange of a girder prop and when the jaws are behind the edges of such flange the sliding arm may be moved to the closed position. The socket *a* may then be brought down to a useful position to receive the lower end of a strut *b* and in moving to such position the cam is rotated and grips the edges of the flange between itself and the claws on the arms. Before being finally tightened the bracket may be raised or lowered on the prop to suit the length of the strut which is to be used. The strut is then fitted and wedged into position and the thrust of the strut on the socket of the bracket effectively tightens the cam grip of the bracket on the prop. The cam contour will be

- suitably proportioned to ensure an effective grip without undue stress or leverage on the arms and for that purpose it has been found that a simple eccentric formation with a 3 inch diameter bar j is welded to the outer ends of the cams on their underside below the socket so that a miner can release the bracket by knocking the ends up without damage to the same.
- 10 There are obviously many modifications which come within the nature of the invention. For example, as shown in Fig. 3, the bracket may be adapted for use with a round prop k , whether of wood or metal, by suitably shaping the cam surface plate l to conform with the periphery of the prop and by providing a shoe plate m to place behind the prop, such plate having ends m^1 to be engaged by the claws n on the ends of the arms n^1 which replace the shorter arms g of the example shown in Fig. 1. This shoe plate m could be chained or pivoted to the arms. Alternatively as shown in Figs. 4 and 5 the body is formed of two cam plates o , to which is attached a bent rod p of round section forming the part engaging the post. In one cam plate is fixed a staple o^1 to which is attached a chain o^2 whilst on the other cam plate are secured angle pieces o^3 between which the links of the chain may be engaged. Preferably a suitable shoe or back plate q is provided to prevent damage to the opposite wall of the post. A similar chain arrangement and shoe could be used with girder section posts. A sprag o^4 is secured between the cam plates o and is suitable for round or H section posts.
- 35 Also, to allow for wear at the spindles or for variation of thickness of the prop flange, plates may be provided adapted to be fitted to the face of the claws of the first described example, and to be secured by tongues which could be bent over the claws or ends of the arms.
- The examples of bracket shown in Figs. 1 to 5 are suitable for use where the loads are moderate, such as to support two or three tons of overhanging coal.
- 45 In a further modification of the first described example, one arm could be slidable on an extension of the spindle and thus avoid the divided spindle construction and the hole in the arm could be elongated to give additional movement for fitting the bracket to the prop. Of course, as shown in Fig. 6, the arms r are made of sufficient length for fitting the bracket to the flange edges of the girder prop with the arms lying against its flanges and having hooks or claws r^1 to lock over the other edges of the flanges. Where the movable arm is slidable on an extension of the spindle any suitable spring loaded or other detent may be provided to prevent sliding movement when the cam has been moved to the locking position and so prevent opening of the arm accidentally or under the stress of thrust from the strut or post.
- As shown in Fig. 7, the bracket is provided with a one-piece spindle s having arms t and t^1 attached thereto, the arm t being fixed while the arm t^1 is pivoted so that it may swing back sufficiently to permit fitting and removal. The pivoted connection embodies a pin t^2 and slot t^3 whilst the back of the hole in the arm is arranged to provide full surface engagement with the end of the spindle. This construction of bracket is particularly suitable for use in the manner shown with steel posts having splayed flanges.
- 75 Where the brackets may be used to form a scaffold, say in a roadway supported by steel

arches; for that purpose, the upper or socket part of the bracket has a V or half round shaped jaw to carry a length of tube, or a length of round timber, upon which cross timbers rest to form a platform.

In such manner of use, brackets are clamped to the arch legs, single brackets only being fitted to the forward arch while an additional bracket on each limb of the rear arch to prevent any tilt of the platform which may be resting on that portion of the side tubes projecting beyond the brackets of the forward arch. These additional brackets are the same as the others but are fitted in an inverted position above the others. Such scaffolding may be used as a safe-guard against small roof falls. Obviously there will be other uses for the brackets forming the subject of this invention. For instance, to strengthen a post a bracket may be used inverted behind the post so as to take an auxiliary post behind and against the main post.

What I claim is:

1. A bracket for attachment to a post comprising a body part formed with a cam face adapted to engage and roll against the side of the post, the complementary means movably connected to the body part and co-acting with the cam face of said body part to form clamping means for gripping the post, the said body part being formed with a platform adapted to receive and support a strut or other member so that the thrust or weight therefrom on the platform operates to roll the cam against the face of the post moving relative to the complementary means and causing it to tighten as a clamp against the post.

2. A bracket for attachment to a post, comprising a body part formed with a cam face adapted to engage and roll against the side of the post, a chain attached to one side of the body part at a point eccentric to the cam face and jaws on the other side of the body part opposite to such point and adapted to receive and hold the chain after it has been passed round the post, said body part being formed with a platform adapted to receive and support a strut or other member so that the thrust or weight therefrom on the platform operates to roll the cam against the face of the post causing it to tighten itself and the chain against the post.

3. A bracket for attachment to a post, comprising a cam-shaped body part having a pivot hole at the cam axis, a pivot shaft in said hole and means carried by said pivot shaft and co-operating with said cam to grip the post, said cam-shaped body part also having a platform adapted to receive and support a strut or other member so that the thrust or weight therefrom on the platform operates to rotate the cam causing it to tighten against the post.

4. A bracket for attachment to a post, comprising a cam-shaped body part having a pivot hole at the cam axis, a two-part pivot shaft in said hole, the parts of which are slidably but relatively non-rotatably associated together, a jaw secured to the outer ends of each part of the shaft adapted to co-operate with the cam to form clamps to grip the post and means for locking the two parts against sliding movement when the jaws and cam are gripping the post, said cam-shaped body part also having a platform adapted to receive and support a strut or other member so that the thrust or weight therefrom on the platform operates to rotate the cam causing it to tighten against the post.
